CARTRIDGE FUSES WITH NON-POROUS ARC-QUENCHING MATERIAL

Louis Joseph Saudicœur, Villeurbanne, Rhône, France, assignor to Lucien Ferraz & Cie, Lyon, Rhône, France, a joint-stock company of France

Filed Mar. 30, 1964, Ser. No. 355,603

Claims priority, application France, Apr. 5, 1963, 43,523, Patent 83,398

3 Claims. (Cl. 200—120)

The present invention relates to cartridge fuses of the kind comprising fusible wires or strips embedded within a mass of arc quenching material between two end caps which carry appropriate contact devices, such as blades or tags.

In the conventional construction the arc quenching material is under pulverulent form and it is enclosed, together with the fusible element, within a tubular body or barrel the ends of which are closed by the end caps. The filing of these cartridge fuses is tedious and delicate. Further the fusible elements are not rigidly maintained by the pulverulent material against the action of shocks, vibrations and accelerations (such as centrifugal force) which may cause their rupture, more particularly when they are brought to a relatively high temperature by passage of their rated electric current.

It has already been proposed to embed the fusible elements in a moulded mass of synthetic resin together with the end caps. But this arrangement has the disadvantage that when the fusible elements are submitted for a long time to a current of relatively high intensity, they are brought to a sufficient temperature for slowly decomposing the synthetic resin, thus producing carbon deposits which are more or less electrically conducting and tend to facilitate the production of the arc in the case of a heavy short-circuit.

In accordance with the present invention the fusible elements are embedded in a moulded mass of compact solid mineral silicate. Such a mass is substantially unaffected by the temperatures which the fusible elements may reach in normal operation and even if some kind of reaction takes place it only leads to the formation of a highly insulating glass.

If desired, the mineral silicate may contain pulverulent silica as a filter. The moulded mass of mineral silicate is preferably enclosed in an outer tubular body or barrel. It is besides possible to provide within the moulded mass a cavity filled with any known arc quenching fluid such as sulphur hexafluoride.

The cartridge fuse according to the invention may be manufactured by first disposing the fusible elements and the end caps in the outer tubular body or barrel, by injecting thereinto a plastic mass of aqueous sodium silicate and in thereafter heating the cartridge at about 150° C. for eliminating the excess of water. The mass then sets in the form of a compact hard solid body.

Pure pulverulent silica may conveniently be added as a filler to the aqueous silicate before proceeding to the injection step. In a modification the pulverulent silica may be introduced into the outer barrel before the injection step.

It is also possible to realize the injection step in a separate mould and thereafter to dispose the solid mass in the outer tubular body or barrel, together with the fusible elements and the end caps.

In the annexed drawings:

FIG. 1 is a longitudinal section of a cartridge fuse according to this invention, comprising an outer barrel.

FIG. 2 is a longitudinal section of a modified embodiment having an inner cavity filled with an arc quenching fluid.

2

Referring to FIG. 1, the contacting blades 1 are formed integral with cylindrical end caps 2 which are fixed by radical screws such as 3 at both ends of an outer tubular body or barrel 4 made of an appropriate insulating material. The end caps 2 comprise inner central bosses 5 on which are soldered the ends of fusible elements 6, such as silver strips. The outer barrel 4 has a lateral hole 4a through which a plastic mass of mineral silicate has been injected into the said outer barrel. This mixture has set in the form of a compact solid body 7 in which the fusible elements are wholly embedded and are thus fully protected against shocks, vibrations or accelerations. Further the silicate mass 7 is unaffected by the temperatures to which the fusible elements may be brought in normal operation, and in any case it could only be transformed into a highly insulating anhydrous glass-like substance without producing any carbon deposit between the end caps 2.

The injection hole 4a is of course sealed by the silicate mixture itself. It is besides obvious that this hole could also be provided in one of the end caps 2. The cross-section of the outer barrel may be circular, square, rectangular, polygonal, or of any other shape, as desired.

The plastic silicate mass is preferably formed of aqueous sodium silicate comprising for instance 60 to 75% water, the cartridge being heated to about 150° C. after the injection step for eliminating the excess of water. Pure pulverulent silica may be added to the plastic mass as a filter.

Alternatively the plastic mass could be injected into a separate mould, the solid body thus obtained being thereafter disposed in the outer barrel together with the fusible elements and the end caps.

The cartridge fuse of FIG. 2 is substantially similar to the embodiment of FIG. 1, but it comprises an inner cavity 8 with a canal which opens laterally through the outer barrel 4, the fusible elements 6 being exposed in the said cavity. This cavity 8 has been filled with an arc quenching fluid, such as sulphur hexafluoride SF₆, and it has been sealed by means of a plug 9. When the fusible elements melt, the arc is immediately quenched by SF₆ in the per se known manner.

The cavity 8 may be realized by means of a small wax core moulded on the fusible elements 6 and disposed in the outer barrel together with these elements. When the silicate mass has been injected and has set, this core is easily eliminated by fusion.

In a modification the sulphur hexafluoride could be contained in a small glass bulb disposed in the central zone of the cartridge and which would break or burst under the action of heat when the fusible elements melt.

While in FIGS. 1 and 2 the end caps 2 have been shown as engaged into the ends of the outer barrel 4, they could also be secured against the end faces of the latter, in the per se known manner.

I claim:

1. A cartridge fuse comprising an open-ended insulating outer tubular barrel having a lateral hole; two electrically conducting end caps, each secured to one end of said barrel so as to define an intermediate inner space therein; electrically conducting fusible elements connecting said end caps with each other within said inner space; and a compact, solid and non-porous mass of a water-soluble mineral silicate embedding said fusible elements and substantially filling said inner space and lateral hole to prevent relative shocks and vibrations of the cartridge fuse assembly.

2. A cartridge fuse comprising an open-ended insulating outer tubular barrel; two electrically conducting end caps, each secured to one end of said barrel so as to define an intermediate inner space therein; electrically conducting fusible elements connecting said end caps with each

other within said inner space; and a compact, solid and non-porous mass of a water-soluble mineral silicate embedding said fusible elements and substantially filling said inner space, said mass having formed therein a substantially central cavity in which said fusible elements are exposed, and said cavity being filled with an arc-quenching fluid.

3. In a cartridge fuse as set forth in claim 2, the tubular barrel and the non-porous mass having registering holes therein through which the arc-quenching fluid is introduced, and a plug insert sealing said registering holes to retain said fluid in said inner space.
